F. P. LOVEJOY,
METAL WORKING TOOL,
APPLICATION FILED APR. 15, 1916.

1,197,136.

Patented Sept. 5, 1916.

UNITED STATES PATENT OFFICE.

FRED P. LOVEJOY, OF SPRINGFIELD, VERMONT.

METAL-WORKING TOOL.

1,197,136.

Specification of Letters Patent.

Patented Sept. 5, 1916.

Application filed April 15, 1916. Serial No. 91,314.

To all whom it may concern:

Be it known that I, FRED P. LOVEJOY, a citizen of the United States, residing at Springfield, in the county of Windsor and State of Vermont, have invented new and useful Improvements in Metal-Working Tools, of which the following is a specification.

This invention relates to metal-working tools, and its object is to provide improved means for securing such tool or tools in a holder.

The invention permits the combination of cutting tools made of the highest grade and most expensive steel, with a holder or holders made of a cheaper grade of steel; and affords substantially as great a degree of rigidity as if the structure were integral. The combination permits adjustment of the tool or tools relatively to the holder, to compensate for wear and resharpening, and, in some cases, for other purposes. I am aware that the combination above mentioned is not broadly new; but the structural features of my combination, hereinafter fully described, afford advantages that are not possible in such combination structures as hitherto provided.

Of the accompanying drawings: Figure 1 represents one embodiment of my invention in what may be considered a top plan view. In this case the tool proper is formed for turning, and it is shown in working relation to a bar of stock. Fig. 2 represents a front elevation of the tool end of the device shown in Fig. 1, the tool proper being shown in the act of turning a chip from the bar of stock. Fig. 3 represents an end elevation of the device as viewed from left to right with reference to Fig. 2. Fig. 4 represents a sectional view in the plane indicated by line 4—4 of Fig. 2. Fig. 5 represents a sectional view, on a larger scale, in a plane indicated by line 5—5 of Fig. 3, the tool proper being in elevation. Fig. 6 represents an elevation of the tool end of a device embodying the invention in a form suitable for boring, or for turning internal cylindric surfaces. Fig. 7 represents a sectional view through the structure intersected by line 7—7 of Fig. 6, excepting that the cutting tool is shown in end elevation. Fig. 8 represents an elevation, partly in section, of a rotary milling cutter, boring head, or sizing reamer, embodying the invention, and including a holder and a plurality of

cutting tools arranged in a series about the axis of the holder. Fig. 9 represents a section through the structure intersected by line 9—9 of Fig. 8. Fig. 10 includes a plurality of cotters in cross section, showing different arrangements of the locking ribs collectively in their relation to their respective cotters. Cotters such as these are adapted to be used with the assemblage shown by Fig. 8, to afford fine adjustment of the cutting tools toward and from the axis of the holder.

The same reference characters indicate the same parts wherever they occur.

Referring first to the form shown by Figs. 1 to 5, the holder, which may be made of relatively cheap steel, is indicated at 12, and the turning tool, which may be made of relatively high grade and more expensive steel, is indicated at 13. In this case, and in all the modifications shown, the shank portion 14 of the cutting tool is cylindric excepting at one side where it is cut away to provide a series of closely related parallel locking ribs 15. These ribs extend transversely with relation to the axis of the shank portion. The holder 12 is provided with a cylindric socket 16 for the reception of the shank portion 14, and with a cylindric socket 17 intersecting the shank-receiving socket. It will be readily understood that the invention is not limited to circular cross section of the shank portion 14 and socket 16, the chief consideration regarding these formations being that they shall conform to each other and permit longitudinal movement of the tool relatively to the holder. The circular cross section, however, would be the cheapest because of the simplicity of boring the socket 16 to the desired size. The shank of the cutting tool is secured in its socket by a cotter 18 that may be made from a cylindric rod. The cotter is provided with a series of ribs 19 arranged to fit between and coact with some of the ribs 15 of the shank portion 14. In order to secure the cutting tool in the most rigid manner, one side of the cotter is faced in a plane at a slight angle to the axis of the cotter, and the ribs 19 are arranged at such angle. The cotter is thus provided with the characteristic feature of a wedge and acts with a tightening effect upon the cutting tool as it is driven against the latter. In the course of driving the cotter the tool will be turned about the axis of its shank portion to position the ribs 15 in parallel relation to

the ribs 19, if the cutting tool is not previously in such position. A predetermined position of the cutting tool, relatively to the axis of its shank, is thus assured when the 5 elements are assembled. Before the cotter is driven the cutting tool may be advanced or retracted relatively to the holder as much or as little as desired, within the range of the series of ribs 15, and from time to time the 10 longitudinal adjustment of the tool may be changed to compensate for wear and resharpening, by driving out the cotter and replacing it after the tool has been moved endwise. The fact that the ribs 15 and 19 15 are closely related affords as fine a degree of adjustment as could be desired, the minimum degree, according to the proportions shown, being about one-fifth or one-sixth of the diameter of the cotter. This fine degree 20 of adjustment is one of the advantages that my invention provides, over some devices hitherto provided.

The essential features of the boring or turning device shown by Figs. 6 and 7 are 25 substantially the same as those of the turning device shown by Figs. 1 to 5, and the same reference characters are, for this reason, applied to indicate the corresponding elements and formations in Figs. 6 and 7.

30 In Figs. 1, 2 and 3 the work is indicated at *a*, while in Fig. 6 the work is indicated at *b*.

The assemblage shown by Fig. 8 may be used as a milling cutter, boring head, or sizing reamer, and comprises a two-part 35 holder, a plurality of cutting tools, and a like number of cotters. The holder comprises a head 20 and a shank 21, the shank having a screw-threaded stud portion 22 screwed into the head so that the two parts 40 are, to all intents and purposes, a unit, although they may be detached from one another. The head 20 is provided with a plurality of shank-receiving sockets 23, arranged in a circular series about the axis of 45 the holder. The shanks 24 of the cutting tools 25 are arranged in the sockets 23, and said shanks are provided with ribs 26 in all respects substantially like the ribs 15 of the form first described. The shanks 24 are secured in the head 20 by cotters 27 respectively, the head being provided with sockets 28 for such cotters. The cotters 27 are provided with locking ribs 29 in all respects 50 similar to the locking ribs of cotter 18, but 55 the cotters 27 differ one from another in the arrangement of the ribs 29 collectively of each cotter. This difference of arrangement is shown by Fig. 10, in which three cotters are shown for the sake of comparison. In 60 Fig. 10 the cotters are identified by the signs #1, #2, #3. Broken lines *x*—*x* intersect the centers or axes of the cotters in this figure, and are provided to show clearly in just what respect the arrangement of the 65 locking ribs differs as between the three

cotters. In cotter #1 the locking ribs are so disposed that the two that are nearest the center line *x*—*x* are equidistant from said line. In cotter #2 the rib that is nearest the center line is at the right of said line, while 70 in cotter #3 the rib that is nearest the center line is at the left of said line. The shape, size and spacing of the ribs are the same in all three cotters, and in other respects, excepting the aforesaid disposition 75 of the ribs collectively, the cotters are alike. They are interchangeable, and in consequence of the difference in the arrangement of locking ribs they are adapted to afford extremely fine adjustments of the cutting 80 tools to vary the effective diameter of the assemblage. For example, if it is desired to change the adjustment of the several cutting tools to increase or decrease the effective diameter of the whole series, cotter #2 may be 85 removed and replaced by cotter #1, cotter #3 may be removed and replaced by cotter #2, and so on around the entire series in the head. The head as shown is designed to take twelve cutting tools, but the number of 90 cutting tools would be optional. However, since it is designed for twelve tools, I have taken three cotters for the basis of comparison in Fig. 10, the difference between cotters #1, #2 and #3 affording three different 95 adjustments within a distance equal to the space between the centers of two contiguous locking ribs. On this basis, assuming that there are four sets of cotters, and three cotters in each set, cotters #4, #7 and #10, 100 #1 would be like cotter #1. Cotters #5, #8 and #11 would be like cotter #2; and cotters #6, #9 and #12 would be like cotter #3. It is to be understood, however, that the cotters may be grouped otherwise than 105 according to the explanation given, depending upon the extent of minimum adjustment desired and upon the number of cutting tools provided.

110 I claim:

1. In combination, a metal-cutting tool having a shank-portion, a holder therefor having a socket conforming to and adapted to receive said shank portion, said holder having a cylindric socket extending substantially at right angles to, and intersecting, said shank-receiving socket, and a substantially cylindric cotter adapted to go into said cylindric socket and engage said shank-portion, said cotter having a plurality of closely related ribs extending at a slight angle to its axis, and said shank-portion having a series of ribs similar to those of said cotter and extending substantially at right angles to the axis of said shank-portion, said ribs of said cotter being adapted to move endwise into coöperative interlocking relation with some of said ribs of said shank-portion.

2. In combination, a plurality of metal- 130

cutting tools each having a shank-portion provided with a series of closely related ribs extending substantially at right angles to its axis, a holder having a plurality of shank-receiving sockets arranged in a series about a common axis, and having a plurality of cylindric cotter-receiving sockets intersecting said shank-receiving sockets respectively, and a plurality of cotters adapted to go into 10 said cotter-receiving sockets, each of said cotters having parallel ribs arranged to fit be-

tween and coat with some of said ribs of the respective shank-portion, said cotters being interchangeable and differing, one from another, as to the arrangement of the 15 ribs collectively, whereby the operative positions of said tools relatively to said holder may be changed in consequence of interchanging said cotters.

In testimony whereof I have affixed my 20 signature.

FRED P. LOVEJOY.
